UNITED STATES PATENT OFFICE.

ALBERT G. MIELKE, OF HOWARD LAKE, MINNESOTA.

LIFTING-JACK.

1,192,667.

Specification of Letters Patent. Patented July 25, 1916.

Application filed April 27, 1916. Serial No. 94,045.

To all whom it may concern:

Be it known that I, ALBERT G. MIELKE, a citizen of the United States, residing at Howard Lake, in the county of Wright, 5 State of Minnesota, have invented certain new and useful Improvements in Lifting-Jacks; and I do hereby declare the following to be a full, clear, and exact description of the invention, such as will enable others 10 skilled in the art to which it appertains to make and use the same.

The present invention is directed to improvements in lifting jacks especially adapted for use in connection with automobiles, 15 and has for its object to provide a device of this character capable of being readily rolled under the axle to be raised and actuated in a simple and easy manner to elevate the axle.

20 A further object of the invention is to provide a jack of this character which is exceedingly simple in construction, durable, and one which can be readily adjusted for use in connection with automobiles having 25 their axles disposed at different elevations.

With the above and other objects in view the invention consists in the details of construction and in the arrangement and combination of parts to be hereinafter more 30 fully described and particularly pointed out in the appended claim.

In describing the invention in detail reference will be had to the accompanying drawing wherein like characters of reference 35 denote corresponding parts in the several views, and in which—

Figure 1 is a top plan view of the device; Fig. 2 is a side elevation of same; Fig. 3 is a rear end view; Fig. 4 is a front elevation; 40 Fig. 5 is a sectional view on line 5—5 of Fig. 1; and Fig. 6 is a sectional view on line 6—6 of Fig. 2.

Referring to the drawings 1 designates a frame which is formed from tubular bars 45 and consists of a main bar 2 one end of which being provided with a coupling 3 which has connected thereto a cross bar 4 the outer ends of which being provided with 50 couplings 5 which are disposed vertically and have threaded in their upper ends tubu-

lar posts 6, said posts being provided with diametrically arranged perforations 7, the purpose of which will appear later.

A lifting frame 8 is provided and is U-shaped, and has supported by its arms 9 55 axle engaging brackets 10. The arms 9 have their ends provided with plugs 11 which are pivotally engaged between the furcations 12 of the rods 13, said rods being provided with vertically spaced perforations 14 which are 60 adapted to register with the perforations 7 formed in the posts 6, after which the pins 15 are passed through the registered perforations to hold the rods in their adjusted positions. The other end of the main bar 2 65 is provided with a coupling 16, which also disposed vertically and has threaded in its upper end a post 17, said post being provided with a stub shaft 18 which is rotatably engaged by the ratchet wheel 19. Cast integral with the wheel 19 is a drum 20 to which is fixed one end of the cable 21 the other end of which being connected to the adjacent end of the lifting frame.

A hand lever 22 is provided and is engaged on the bolt 23 which passes through the stub shaft 18, said lever having a pawl 24 carried thereby for engaging the teeth of the wheel 19, whereby when the lever is rocked rotary movement will be imparted 80 to the drum 20 thus winding the cable 21 thereon sufficiently to swing the frame 8 upwardly so that the axle engaged with the brackets 10 will be elevated as desired.

A spring pressed pawl 25 is supported by 85 the post 17 and engages the wheel 19 to hold the same against accidental rotation, said pawl having connected to one end a cord 26 so that the pawl can be tripped after the lever 22 has been actuated sufficiently to permit the pawl 25 to disengage the wheel 19.

The couplings 5 and 16 are provided with 90 caster wheels 27, whereby the device can be conveniently rolled from place to place and under the axle to be elevated.

What is claimed is:—

A jack of the class described comprising 95 a frame consisting of a main bar, a cross bar carried by one end of the main bar, tubular posts connected with the ends of the 100

cross bar, rods adjustably mounted in the posts, a lifting frame pivotally connected to the rods, a post connected with the other end of the main bar, and means supported by the last named post for swinging the lifting frame.

In testimony whereof, I affix my signature, in the presence of two witnesses.

ALBERT G. MIELKE.
